MANUFACTURE OF THREAD BANDS FROM
ARTIFICIAL SILKGiovanni Campolunghi, Rome, Italy, assignor to
Societa Anonima Minerva, Rome, Italy, a limited company of ItalyApplication November 27, 1935, Serial No. 51,963
In Italy November 30, 1934

3 Claims. (Cl. 18—54)

According to the known process for the continuous manufacture of thread bands from artificial silk the band supplied from the spinning machine is taken over immediately by the washing device and is supplied at the same speed at which it was spun through a row of containers, in which it undergoes various treatments (sulphur-removal, bleaching, reviving) or even washing processes before and after the different treatments.

The subject of the invention is a process for the continuous manufacture of thread bands from artificial silk which is more particularly characterised by the fact that it produces a complete independence between the spinning machine and the washing machines.

The advantages resulting from the new process as compared with the first mentioned known process are of many kinds, and of great importance.

Above all, the operating conditions of the spinning machine and the washing machine can now be freely altered, without any reciprocal combination in accordance with the working requirements at any time. Possible stops and interruptions of work in the treatments in the baths no longer require the stopping of the spinning machine, thus fulfilling an essential preliminary condition for high production from the spinning machine. The washing machines can now run at a slower speed than the spinning machine and several bands can be treated simultaneously on the washing machines, and the containers which are now traversed by the bands at a slower rate can be made correspondingly shorter and nevertheless produce an equal or higher output.

Moreover the new process assures the complete coagulation of the spun artificial silk before the treatment in the washing or sulphur removing baths begins since now it need no longer happen that an incompletely coagulated material is supplied into the baths.

The process according to the invention enables thread bands of artificial silk, which on account of certain working requirements were not completely coagulated, to be further treated by mechanical means. In these cases the thread band collected at the outlet of the spinning machine is treated with a suitable coagulating bath before it is given over to the washing device.

The independence between the spinning machine and the washing machine can be produced without adversely affecting the continuity of the process if the thread band of artificial silk, on

its discharge from the spinning machine, is stored by means of a suitable device in special containers from which this band can then be removed by the washing machine.

Such a device is illustrated schematically by way of example in the drawing and in which:

Fig. 1 is a view, partly in elevation and partly in section.

Fig. 2 is a plan of a band distributor which seizes the thread band 1 upon its discharge from the spinning machine 2 and stores it in suitable receivers 3 in such a way that it can be subsequently drawn off by a washing machine 4 without danger of tangling.

In practice it has been found to be preferable to use two rows of boxes of rectangular cross section as receivers from the spun thread band, the number in each row corresponding to the number of bands which the washing machine treats simultaneously in the above described manner.

Whilst one row of boxes 3 is filled with spun thread band by means of the distributor 5 of the spinning machine the other row of boxes 3' (which has been filled in a previous operation) can be emptied to supply the washing machine.

The band distributor 5 must be so arranged that it first of all gives a drawing off movement in the direction of the band axis (arrow a) and then two movements extending transversely to each other in order to fill each box correctly (arrow b). Moreover it must move from box to box in each row in order to fill successively all the boxes in this row progressively in the direction of the axis of each row (arrow c) and finally after filling one row it must be guided transversely to the direction of the arrow c over the adjacent row of empty boxes (arrow d) in order to fill these boxes in a subsequent working period. All these movements can be easily carried out as automatic movements.

What I claim is:

1. Process for the continuous manufacture of staple fiber wherein a band of endless fiber coming from a spinning machine is subjected to a treatment such as washing, sulfur removing, bleaching, reviving and the like, comprising continuously depositing the single band coming from the spinning machine consecutively in the containers of a first set of containers, and contemporaneously removing the deposited band simultaneously from a plurality of containers of a previously filled set of containers in the form of a plurality of bands and conveying the latter to the point of treatment, whereby the removing

operation may be effected at a lower rate of speed than the depositing operation.

2. Process for the continuous manufacture of staple fiber wherein a band of endless fiber coming from a spinning machine is subjected to a treatment such as washing, sulfur removing, bleaching, reviving and the like, comprising continuously depositing the single band coming from the spinning machine consecutively in the 5 containers of a first set of containers, and contemporaneously removing the deposited band simultaneously from a plurality of containers of a previously filled set of containers in the form of a plurality of bands and conveying the latter 10 to the point of treatment, and continuing the 15

alternate depositing and removing operations with reference to one set of containers while contemporaneously alternately removing and depositing with reference to the other set of containers, whereby the removing operation may be effected at a lower rate of speed than the depositing operation and uncoagulated material coming from the spinning machine may complete their coagulation before being subjected to further treatment.

3. The process defined in claim 2, coagulating liquid being applied to the deposited band in said containers.
